United States Patent

Des. 238,063

Patented Dec. 16, 1975

238,063

WHEEL CENTER

Richard H. Clement, 10900 Jann Court,
La Grange, Ill. 60525

Filed Nov. 5, 1973, Ser. No. 412,805

Term of patent 14 years

The term of this patent subsequent to Jan. 9, 1987,
has been disclaimed

Int. Cl. D12—16
U.S. Cl. D12—209

FIG. 1

FIG. 2

FIG. 3

FIG. 4

FIG. 1 is a top plan view of a wheel center showing my new design;

FIG. 2 is a side elevational view thereof;

FIG. 3 is a fragmentary sectional view thereof, taken along line 3—3 in FIG. 1; and

FIG. 4 is a top plan view of a wheel center showing a second embodiment of my new design, wherein the sole difference resides in the addition of a bolt hole.

I claim:

The ornamental design for a wheel center, as shown.
